REFRIGERANT CONTAINER

Vinton E. Sisson, Winnetka, Ill., assignor to
Standard Railway Devices Company, a corpora-
tion of Delaware

Application December 8, 1938, Serial No. 244,535

6 Claims. (Cl. 62—17)

This invention relates to refrigerator cars used to transport perishable commodities at a predetermined temperature. The essential features of such a car are an insulated structure and a refrigerating means for use in warm weather or a heating means for use in cold weather.

The invention relates particularly to refrigerator cars of the overhead bunker type. Cars of this type have the refrigerant containers suspended immediately below the roof. They are often provided with drip pans below the containers to form refrigerant compartments below the roof and adjacent the side walls of the car. It is also common to provide vertical flues associated with the side walls and extending to near the floor. These flues serve as passages for the flow of refrigerated air from the refrigerant compartment to below the floor racks of the car so that it may circulate upwardly through the lading. The flues also serve to drain off melted refrigerant when a foraminous or semi-foraminous container is used or condensation from the container when liquid-retaining tanks are used.

The principal object of the invention is to prevent the surging and splashing of refrigerant within the containers due to service movements of the car. The refrigerant usually used in refrigerator cars consists of a frozen liquid which melts upon absorbing heat from the lading. In some types of cars all of the liquid is retained while in others, only a portion is retained and the remainder allowed to spill through a foraminous upper portion of the container. In either case, the refrigerant usually comprises a mixture of liquid and solid which may have very harmful effects as it surges from side to side and from end to end of the container.

The surging may cause liquid and even solid refrigerant to splash out of the container upon parts of the car not intended to be moist. For example, the efficiency of the insulation could be greatly decreased by the presence of moisture therein. The deterioration of wood parts would be accelerated while metal parts would be rapidly corroded, particularly if the refrigerant contains salt. The liquid might even fall upon the lading and cause damage thereto with a resultant financial loss. Another harmful effect would be the loss of refrigerant within the container with a consequent loss of refrigeration efficiency.

Another harmful effect of surging of refrigerant, particularly in containers positioned near the roof of the car, is the rocking and swaying of the car in a direction transverse to the direction of motion of the car. It is difficult to deter-

mine whether the surging of the refrigerant is the cause or the result of the swaying of the car but it is likely that each contributes to the other. Therefore, a retardation in the surging of the refrigerant would probably be accompanied by less swaying action.

Railway cars are often subjected to sudden starting and stopping which has a tendency to induce surging of the refrigerant. Effects of violent surging may be disastrous as, for example, overstraining of the containers and of the superstructure of the car as well as loss of refrigerant. It is an object of this invention to retard, not only the transverse surging of the refrigerant, but surging longitudinally of the car as well.

In refrigerator cars of the overhead bunker type, it is important that the refrigerant containers occupy substantially all of the space immediately below the roof. This is necessary to obtain the required amount of refrigerant capacity without unnecessarily increasing the height of the car. It is impractical, however, to build a car having the area of the hatches as large as the container area because such an arrangement would greatly impair the insulation of the car and would result in hatches too large to be conveniently handled. Therefore, parts of the containers underhang those portions of the roof adjacent the hatches. When refrigerant is loaded into the containers, it is usually placed first in the part of a container immediately under the hatch and then pushed along the bottom of the container by a shovel, paddle, or similar instrument, to the marginal parts of the container. It is an object of this invention, then, to provide baffles within the container to prevent surging of the refrigerant. It is a further object to arrange said baffles so as not to interfere with the loading of the refrigerant as heretofore described.

Another object of the invention is to provide means to keep the liquid level approximately equal in all sections of a container. It is desirable to evenly distribute the refrigerant throughout the container so as to keep the refrigerating efficiency high. It is a further object to provide communication between the sections to facilitate draining of liquid therefrom. Small openings in the above-mentioned baffles keep the liquid level constant on both sides thereof without materially decreasing the efficiency of the baffles in retarding surging of the refrigerant. Said openings also permit draining of the entire container through only one drain. It is another object of the invention to provide

some of said baffles higher than others of said baffles, the baffles extending transversely of the car preferably being higher to further retard the surging of the refrigerant caused by the violent and sudden stopping and starting of the car.

Other advantages and objects of the invention will be apparent from the following detailed description by referring to the drawings in which:

Fig. 1 is a partial transverse section of a refrigerator car equipped with semi-foraminous refrigerant containers and embodying my invention.

Fig. 2 is a section on line 2—2 of Fig. 1.

Fig. 3 shows a modified design.

Figs. 4 and 5 are perspective views of imperforate liquid-retaining containers embodying modified forms of my invention.

Fig. 6 is a diagrammatic plan view of the container shown in Figs. 1 and 2.

Figs. 7 to 12 inclusive are diagrammatic plan views of modified designs.

The usual parts of a refrigerator car are shown in Figs. 1 and 2, such as, side plate 2, side sheathing 3, roof 4, running board 5, ceiling 6, hatch frame 7 surrounding the hatch 8, center duct wall 9, drip pan 10, side lining 11, false wall 12 providing the flue 13, insulation 14, and refrigerant container 15. The refrigerant container 15 is shown having a foraminous upper portion 16 and an imperforate lower portion 17. The container 15 comprises a bottom 18 and substantially vertical end walls 19 and side walls 20.

As shown in Figs. 1 and 2, the container 15 is provided with a plurality of baffles 25 which extend longitudinally of the car or parallel with the side walls 20 of the container 15 to retard surging of the refrigerant laterally of the car. A baffle 26 extends transversely of the car or parallel with the end walls 19 of the container 15 to retard surging longitudinally of the car. The baffles 25, 26 preferably extend from the bottom 18 of the container 15 upwardly substantially to the lower edge of the foraminous portion 16 and may be, although not necessarily so, provided with openings, such as, at 27 or 28, near the bottom 18 of the container 15. The baffles 25, 26 may be spaced above the bottom 18 of the container 15 to provide communication between various sections of the container.

Fig. 3 shows a refrigerator car equipped with an imperforate tank 30 designed for complete retention of liquid refrigerant. The transversely extending baffle 33 has increased height because the longitudinal movement of the car, i. e., the sudden starting and stopping, are likely to be more severe than the lateral swaying of the car.

Fig. 4 is a diagrammatic perspective view of a tank similar to the imperforate tank 30 of Fig. 3. The dotted line 35 represents the lowermost edge of the hatch frame, i. e., the edge 36 in Fig. 3. Fig. 4 illustrates a design in which the baffles 37 extend from the bottom 18 of the tank 30 substantially to the lower edge 35 of the hatch frame. The baffles 37 are notched under the hatch to provide depressed portions 38 which facilitate the loading of refrigerant through the hatch opening 35 to the remote ends of the tank 30.

Fig. 5 shows a tank 30 similar to that shown in Fig. 4 wherein the dotted line 35 also indicates the lower edge of the hatch frame. The baffle 42 is shown notched, the notch extending to the bottom of the tank 30 to provide a communicating channel 43 between the sections of the tank 30 formed by the baffle 42.

Fig. 6 is a diagrammatic plan view of the construction shown in Figs. 1 and 2 showing that the baffles 25, 26 divide the refrigerant container 15 into a plurality of sections 50. A portion of each section 50 underlies the hatch opening, i. e., the area bounded by the dotted line 35 of Fig. 6. The refrigerant may be loaded through the hatch to each section and pushed along the bottom of the container 15 to the remote parts thereof.

Fig. 7 shows a container 15 having only one longitudinal baffle 55 and Fig. 8 shows the container 15 having three longitudinal baffles 56, each having one transverse baffle 57. In each case, the container is divided into a plurality of sections 50, each section having a portion underlying the hatch opening 35. The number of longitudinal baffles required is largely a matter of personal opinion, depending upon other features of the car design, the type of service in which the car is to be used, and other factors.

In some cases, it may be preferable not to provide a transverse baffle as shown in Fig. 9. Any number of longitudinal baffles may be provided, but only one (60) is shown. The baffle 60 divides the container 15 into two sections 50, either of which may be conveniently loaded through the hatch.

Fig. 10 illustrates an arrangement in which a plurality of baffles extend radially from a point 65 under the hatch 35. Some of the baffles 66 are shown parallel with the side walls 20 of the container 15, some (67) parallel with the end walls 19, and others (68) extending diagonally between corners of the container. The invention is not limited by the convention shown but includes any arrangement in which the point 65 is under the hatch 35 and has the baffles extending radially therefrom so that a portion of each section 50 formed by the baffles underlies the hatch.

Fig. 11 shows three longitudinally extending baffles 70 which divide the container 15 in four sections 50, each having a portion underlying the hatch 35.

In Fig. 12, the container 15 is provided with two longitudinal baffles 75 and two transverse baffles 76 which divide the container 15 into a plurality of sections, each section having a portion underlying the hatch 35.

It is apparent that a large number of modified forms of my invention could be developed. The type of car, the service in which it is used, the type of refrigerant used, and many other factors may necessitate changes in design beyond the modifications shown herein. My invention includes any arrangement of substantially vertical baffle plates within the container positioned to permit easy loading of refrigerant to all parts of the container.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having a roof provided with a hatch and a refrigerant container below said roof and positioned to be loaded through said hatch, said container comprising a bottom and upstanding walls, a substantially vertical baffle within said container to retard surging of a refrigerant in said container due to service movements of the car, said baffle extending substan-

tially to the top of said container and being notched adjacent said hatch to facilitate loading, said baffle dividing said container into a plurality of sections, each section having a portion underlying said hatch.

2. In a refrigerator car having a roof provided with a hatch and a refrigerant container below said roof and positioned to be loaded through said hatch, said container comprising a bottom and upstanding walls, substantially vertical baffle means positioned within said container, other substantially vertical baffle means arranged in angular relation with the first mentioned baffle means, said baffle means all cooperating to divide the interior of the container into a plurality of sections each having a portion underlying said hatch to provide a passage for loading refrigerant through said hatch into each section, said baffle means extending upwardly to the top of said walls adjacent thereto and being reduced in height below said hatch to facilitate loading.

3. In a refrigerator car having a roof provided with a hatch and a refrigerant container below said roof and positioned to be loaded through said hatch, said container comprising a bottom and upstanding side and end walls, substantially vertical baffle means positioned within said container and other substantially vertical baffle means positioned within said container arranged in angular relation to said first mentioned baffle means, said baffle means all cooperating to divide the interior of the container into a plurality of sections each having a portion underlying said hatch to provide a passage for loading refrigerant through said hatch into each section, the upper edges of said baffle means being notched below said hatch to increase the size of said passages.

4. In a refrigerator car having a roof provided

with a hatch and a refrigerant container below said roof and positioned to be loaded through said hatch, said container comprising a bottom and upstanding side and end walls, substantially vertical baffle means positioned within said container parallel with the side walls of the container and other substantially vertical baffle means positioned within said container parallel with the end walls of the container extending to a greater height above the bottom of the container than said first mentioned baffle means, said baffle means all cooperating to divide the interior of the container into a plurality of sections each having a portion underlying said hatch to provide a passage for loading refrigerant through said hatch into each section.

5. In a refrigerator car having a roof provided with a hatch and a refrigerant container below said roof and positioned to be loaded through said hatch, said container comprising a bottom and upstanding walls and a substantially vertical baffle extending between opposite walls of the container so as to brace said walls and positioned below said hatch so that the portion of the container on either side of said baffle may be loaded through said hatch, said baffle being notched below said hatch to facilitate such loading.

6. In a refrigerator car having a roof provided with a hatch and a refrigerant container below said roof and positioned to be loaded through said hatch, said container comprising a bottom and upstanding walls, and substantially vertical baffles extending from opposite walls of the container and merging into the bottom of the container so as to brace said walls and positioned below said hatch so that the portion of the container on either side of said baffle may be loaded through said hatch.

VINTON E. SISSON.
